UNITED STATES PATENT OFFICE.

CARL HEINRICH KOERNER, OF HAMBURG, GERMANY.

BOOK-REST.

SPECIFICATION forming part of Letters Patent No. 595,779, dated December 21, 1897.

Application filed May 12, 1897. Serial No. 636,261. (No model.)

To all whom it may concern:

Be it known that I, CARL HEINRICH KOERNER, a subject of the German Emperor, and a resident of Hamburg, in the German Empire, 5 have invented certain new and useful Improvements in Rests for Use with Large Account-Books and the Like, of which the following is a specification.

The present invention relates to improvements in rests for use with large account-books and the like, the object being to make such rests more expedient and handy by attaching the usual tongue to be placed between the leaves of the book in such a manner to the 15 actual supporting-plate that it may be shifted either to the right or to the left end of the supporting-plate; and with this end in view my invention consists of certain novel features of construction and combinations of 20 parts, as hereinafter will be fully described.

A rest made according to my invention is illustrated in the accompanying sheet of drawings, in which—

Figure 1 is a perspective view of the improved rest as applied to a book; Fig. 2, a view showing the lower side of the rest; Fig. 3, a cross-section on the line III, Fig. 2. Fig. 4 is a similar view as Fig. 2, the tongue being adapted to slide along a longitudinal guide-groove of the supporting-plate. Fig. 5 illustrates a side view of Fig. 4, and Fig. 6 a sectional end view of a modification of my improved rest when applied to a book.

Similar letters refer to similar parts throughout the several views.

The improved rest, adapted for use more particularly in making entries in large-sized account-books, consists of the well-known supporting-plate *a* and of the tongue *b*, arranged at an angle to the same. This tongue may be shifted either to the right or to the left end of the said supporting-plate, for which purpose it is inserted into one of the transverse guides or slideways *a'*, provided 45 on the supporting-plate *a*, Figs. 2 and 3, or the said tongue *b* may be slid along a longitudinal guide-groove *a*², with which the said plate *a* may be provided, Figs. 4 and 5. The tongue *b* is in the usual manner placed between the leaves of the book into which entries are to be made, while the free end of the supporting-plate rests upon the opposite

part of the open book with a finger *c*. For the reception of the said finger *c* the supporting-plate *a* may be provided at each end with 55 a dovetailed groove, the finger *c* being constructed to fit such groove, so that one and the same finger is adapted to engage with either groove, as required, or there may be inserted into each of the grooves a finger 60 adapted to slide backward and forward after the manner of a bolt, so that according as the tongue *b* is placed upon the right-hand or the left-hand side of the book one of the said fingers, either on the left or on the right, 65 is placed over the book edge. In addition to this, when it is desired to write on the half of the book which, in the horizontal position, does not touch the table-surface, such half may be supported by a separate rest *d*, provided with step-like notches or offsets, a feature which will prove particularly advantageous in those cases where the book portion so supported is considerably thinner than the remaining part of the book. 70

The arrangement herein described affords a convenient and reliable rest to persons engaged in making entries in an account-book, especially where large-sized books are used, as well as where entries have to be made on 80 both sides of a book.

In a slightly-modified form of the improved writing-rest the supporting-plate proper is formed of two portions or halves *a*³ *a*³, hinged or otherwise movably connected, as shown at 85 *a*⁴, Fig. 6. For the central guide *a'*, provided for the tongue *b* in the arrangement first described, there are here accordingly substituted two guide-rails *a'* *a'*, one upon each half *a*³. A double or folding supporting-plate 90 such as this enables the offset-rest *d*, mentioned above, to be dispensed with, as such plate, owing to its movable point, is capable of accommodating, if necessary, the angular shape of the open book. (See Fig. 5.) Besides, a writing-rest comprising such a double and folding plate *a*³ *a*³ affords the advantage that it may be folded up into compact shape when not in use. 95

Having fully described my invention, what I claim, and desire to secure by Letters Patent, is—

1. A book-rest comprising a rest-plate *a* of a length substantially equal to the width of

an open book, a retaining-plate *b* adapted to be shifted from one side to the other of the longitudinal center of said rest-plate, the latter provided near each end with a retaining-
5 groove and a finger *c* fitting either of said grooves, substantially as and for the purpose set forth.

2. A book-rest comprising a rest-plate *a*, of a length substantially equal to the width of an open book, said plate composed of two plates hinged together, a retaining-plate *b*, shiftable from one to the other side of the hinge-joint of said rest-plate, the latter provided near each end with a retaining-groove
10 and a finger fitting either groove, substantially as and for the purpose set forth.

15 3. A book-rest comprising a rest-plate *a* of

a length substantially equal to the width of an open book, a retaining-plate *b*, shiftable from one to the other side of the longitudinal center of said rest-plate, the latter provided near each end with a retaining-groove and a finger fitting either groove, in combination with the stepped rest *d*, substantially as and for the purpose set forth.

20 In testimony that I claim the foregoing as my invention I have signed my name, in presence of two witnesses, this 24th day of April, 1897.

25 CARL HEINRICH KOERNER.
